SWATCH

Rudolph Weinlich, Brooklyn, N. Y.

Application December 10, 1938, Serial No. 244,943

11 Claims. (Cl. 35—56)

This invention relates to cloth or textile fabric swatches, the object of the invention being to provide an improved cloth or textile fabric swatch which will disclose the different colors, combinations of colors, weights or textures of goods available in the pattern corresponding to the particular swatch, and which may readily be removed and replaced by others as the colors, etc., are changed, and which will be visible at all times, thereby avoiding the necessity of having a multitude of swatches corresponding to the various colors, weights and textures of each pattern, thus eliminating the necessity of cutting up many bolts of cloth to furnish such swatches.

Heretofore, in the selling of many classes of goods such, for instance, as men's suitings, by travelling salesmen and also in the shops, it has been the almost universal practice to display the same by means of samples of comparatively large size commonly called swatches since it is not always practicable even for a store, to carry large quantities of various patterns and kinds of material in the form of bolts of cloth. Consequently, since all goods usually come in different textures, weights, colors or combinations of colors, it was necessary to have a swatch of each weight and color, etc., to enable the customer to choose therefrom.

In short, if a particular pattern of cloth was made up in ten colors or combinations of colors and in several weights, etc., it was necessary to have for ten colors and three weights for each color, thirty or more swatches of that particular pattern and as each of these swatches was of considerable size and frequently of double thickness, obviously, many bolts of cloth were consumed in the manufacture of such swatches for the salesmen and the stock of the retailers, a very expensive procedure and which expense, of course, had to be added to the cost of the merchandise.

By the present improvement, the making of a swatch for each type or color of cloth is avoided and a single swatch of a particular pattern is provided accompanied by a set of small samples to show the various colors, textures and weights of cloth available and the swatch is so constructed that the samples are always visible and may be readily removed and others substituted when the colors and other details are changed.

Therefore, it is the object of the present improvement to reduce materially the expense and very much simplify the selling of the goods in a more expeditious manner.

In the drawings accompanying and forming a

part of this specification, Fig. 1 illustrates a swatch having the present improvement.

Fig. 2 is a perspective view of the detachable holder for the small samples or specimens.

Fig. 3 is a transverse vertical section taken on the line 3—3 of Fig. 1, with the sample holder omitted, and

Fig. 4 is a perspective view of a swatch arranged to carry several sets of samples and preferably arranged in book form so that the book may contain one or more additional leaves of samples.

Similar characters of reference indicate corresponding parts in the several views.

Before explaining in detail the present improvement and mode of operation thereof, I desire to have it understood that the invention is not limited to the details of construction and arrangement of parts illustrated in the accompanying drawings since the invention is capable of other embodiments, and that the phraseology employed is for the purpose of description and not of limitation.

The swatch of material 2 usually having its edges pinked or bound and of either single or double thickness is provided with a covered portion 3, the area of which is usually less than the uncovered part 4 of the swatch and this covered portion consists of a transparent covering sheet of material 5 so stitched or bound to one face of the swatch that it will form a receptacle or pocket preferably open at its ends for the reception of a holder 6 comprising a card preferably of double thickness and connected along the edges and carrying a series of small samples 7 of different colors, grades or weights of the material, which samples are preferably so arranged on the holder as to overlap and also preferably carried by independent holders or strips 8 readily detachable from or attachable to the holder 6.

In the form shown in Figs. 1 and 2, the receptacle of the swatch has a holder 6 therein carrying ten different colored specimens or samples 7, each mounted upon its own individual holder or strip 8, the ends of which are readily insertable into slots 9 located along the edges of the holder 6 so that the entire holder may be detached from the swatch and replaced by another or any one or more of the various colors may be detached from the holder and replaced by others.

The holder 6 is shown provided with eight openings 10 which permit data with relation to the various samples to be seen therethrough.

One of the advantages of this improved swatch

is that the specimens may be easily handled without being soiled since they are protected by the transparent cover and thus maintained in a neat and clean condition while, at the same time, 5 they are always visible.

If desired, several holders may be carried in receptacles, each having a transparent face secured to the swatch side by side, one form of which is shown in Fig. 4 wherein the swatch is 10 arranged in book form so that a greater number of samples may be carried by the same swatch and for this purpose, the swatch has one face thereof provided with a transparent covering sheet 5' secured thereto preferably by being 15 stitched along its edges crosswise of the swatch and shown extending substantially from edge to edge thereof, as in Fig. 1, thus providing a receptacle for a removable holder 6' which, in this form, has overlapping side edges 9' for the 20 reception of individual holders 8' carrying the different samples, whereby each may be readily removed from the holder.

Secured to one end of the swatch, preferably by being bound thereto to form a hinge, is a leaf-formed receptacle 12 likewise having a transparent covering sheet 13 for the reception of a main holder similar to either of those hereinbefore described and, therefore, adapted to carry individual sample holders 8' located side by side, 30 preferably cross-wise of the swatch so that the swatch may be readily folded into compact book form.

It is to be understood that, by describing in detail herein any particular form, structure or 35 arrangement it is not intended to limit the invention beyond the terms of the several claims or the requirements of the prior art.

Having thus explained the nature of my said invention and described a way of constructing 40 and using the same, although without attempting to set forth all of the forms in which it may be made, or all of the modes of its use, I claim:

1. A relatively large swatch of cloth or textile fabric of sufficient size to drape over the arm 45 or leg and having on a face thereof a pocket of materially less size than the swatch and having therein a removable supporting holder carrying in juxtaposition for ready comparison with each other and with the larger swatch, a set of smaller swatches of the same pattern but of different weights or colors whereby a single large swatch with its associated small swatches will take the place of many large swatches.

2. A relatively large foldable swatch of cloth 55 or textile fabric of sufficient size to drape over the arm or leg and having on a face thereof a transparent-faced pocket of materially less size than the swatch and having therein a removable supporting holder carrying in juxtaposition for ready comparison with each other and with the larger swatch a set of smaller swatches of the same pattern but of different weights or colors whereby a single large swatch with its associated smaller swatches will take the place of many 60 large swatches.

3. A relatively large foldable swatch of cloth 70 or textile fabric of sufficient size to drape over the arm or leg and having on a face thereof a transparent-faced pocket of materially less size than the swatch and having therein a removable supporting holder carrying in juxtaposition for ready comparison with each other and with the larger swatch a set of smaller swatches of the same pattern but of different weights or colors, 75 and independent holders removable with or from

said supporting holder and each carrying one of the smaller swatches, whereby a single large swatch with its associated smaller swatches will take the place of many large swatches.

4. A relatively large foldable swatch of cloth 5 or textile fabric of sufficient size to drape over the arm or leg and having on a face thereof a transparent-faced pocket of materially less size than the swatch and having therein a removable supporting holder carrying in juxtaposition for 10 ready comparison with each other and with the larger swatch a set of smaller swatches of the same pattern but of different weights or colors, and independent holders removable with or from said supporting holder and each carrying one of 15 the smaller swatches, said supporting holder having a row of aligned slots for the reception of the independent swatch holders carrying the smaller swatches and adjacent thereto a row of sight openings, whereby a single large swatch with its 20 associated smaller swatches will take the place of many large swatches.

5. A relatively large swatch of cloth or textile fabric comprising a pair of layers of material folded upon itself and of sufficient size to drape 25 over the arm or leg and having on the face thereof a transparent-faced pocket of materially less size than the swatch and having therein a removable supporting holder carrying in juxtaposition for ready comparison with each other and with the larger swatch a set of smaller 30 swatches of the same pattern but of different weights or colors whereby a single large swatch with its associated smaller swatches will take the 35 place of many large swatches.

6. A relatively large swatch of cloth or textile fabric of sufficient size to drape over the arm or leg and having on a face thereof a pocket of materially less size than the swatch and having therein a removable supporting holder carrying in juxtaposition for ready comparison with each other and with the larger swatch a set of smaller swatches of the same pattern but of different weights or colors, 40 said large swatch having a leaf secured to one edge thereof and also carrying a 45 pocket having therein a removable supporting holder carrying in juxtaposition for ready comparison with each other and with the larger swatch a set of smaller swatches of the same pattern but of different weights or colors, whereby 50 a single large swatch with its associated smaller swatches will take the place of many large swatches.

7. A relatively large foldable swatch of cloth 55 or textile fabric of sufficient size to drape over the arm or leg and having on a face thereof a transparent-faced pocket of materially less size than the swatch and having therein a removable supporting holder carrying in juxtaposition for ready comparison with each other and with the larger 60 swatch a set of smaller swatches of the same pattern but of different weights or colors, said swatch having a leaf secured to one edge thereof and also carrying a transparent-faced 65 pocket of substantially the same size as the first pocket and having therein a removable supporting holder carrying in juxtaposition for ready comparison with each other and with the larger swatch a set of smaller swatches of the same pattern but of different weights or colors, whereby a single large swatch with its associated smaller swatches will take the place of many large 70 swatches.

8. A relatively large foldable swatch of cloth 75

or textile fabric of sufficient size to drape over the arm or leg and having on a face thereof a transparent-faced pocket of materially less size than the swatch and having therein a removable 5 supporting holder carrying in juxtaposition for ready comparison with each other and with the larger swatch a set of smaller swatches of the same pattern but of different weights or colors, said swatch having a leaf secured to one edge 10 thereof and also carrying a transparent-faced pocket of substantially the same size as the first pocket and having therein a removable supporting holder carrying in juxtaposition for ready comparison with each other and with the larger 15 swatch a set of smaller swatches of the same pattern but of different weights or colors and independent holders removable with or from the supporting holder and each carrying one of the smaller swatches, whereby a single large swatch 20 with its associated smaller swatches will take the place of many large swatches.

9. A relatively large swatch of cloth or textile fabric comprising a pair of layers of material folded upon itself and of sufficient size to drape 25 over the arm or leg and having on the face thereof a transparent-faced pocket of materially less size than the swatch and having therein a removable supporting holder carrying in juxtaposition for ready comparison with each other and with the larger 30 swatch a set of smaller swatches of the same pattern but of different weights or colors, said swatch having a leaf secured to an edge thereof and also having a transparent-faced pocket having therein a removable supporting 35 holder carrying in juxtaposition for ready comparison with each other and with the larger swatch a set of smaller swatches of the same pattern but of different weights or colors and an independent holder removable with or from the main 40 holder and each carrying one of the smaller swatches, whereby a single large swatch with its associated smaller swatches will take the place of many large swatches.

10. A relatively large foldable swatch of cloth 45 or textile fabric comprising a pair of layers of

material folded upon itself and of sufficient size to drape over the arm or leg and having on a face thereof a transparent-faced pocket not exceeding substantially one-half the size of the foldable swatch and having therein a removable supporting holder carrying in overlapping relation for ready comparison with each other and with the larger swatch a considerable number of smaller swatches of the same pattern but of different weights or colors and an independent holder removable from or with the main holder and each carrying one of said smaller swatches whereby a single large swatch with its associated smaller swatches will take the place of many large swatches. 5

11. A relatively large foldable swatch of cloth or textile fabric comprising a pair of layers of material folded upon itself and of sufficient size to drape over the arm or leg and having on a face thereof a transparent-faced pocket not exceeding substantially one-half the size of the foldable swatch and having therein a removable supporting holder carrying in overlapping relation for ready comparison with each other and with the larger swatch a considerable number of smaller swatches of the same pattern but of different weights or colors, and an independent holder removable from or with the main holder and each carrying one of said smaller swatches, said large swatch having secured to one edge 20 thereof a leaf of substantially the same size as the transparent pocket of the large swatch and also having a transparent pocket, a removable supporting holder therein carrying in overlapping relation for ready comparison with each other and with the larger swatch a considerable number of smaller swatches of the same pattern but of different weights or colors and an independent holder removable with or from the main holder and each carrying one of the smaller swatches whereby a single large swatch with its associated smaller swatches will take the place of many large swatches. 25
